UNITED STATES PATENT OFFICE.

FRANK G. TERRY, OF SALINAS, CALIFORNIA.

BEET-SHREDDER.

1,260,732.

Specification of Letters Patent. Patented Mar. 26, 1918.

Application filed November 16, 1916. Serial No. 131,726.

To all whom it may concern:

Be it known that I, FRANK G. TERRY, a citizen of the United States, residing at Salinas, in the county of Monterey and State of California, have invented certain new and useful Improvements in Beet-Shredders, of which the following is a specification.

This invention relates to vegetable cutters, particularly beet-shredders, and especially 10 to knives for beet-shredders of the type in which the knives are arranged in the revolute bottom of a stationary cylindrical hopper, the beets being brought into contact with the knives to perform the shredding 15 by the revolution of the hopper bottom in conjunction with the superimposed weight of the mass of beets upon the knives.

The knives now in use in this type of shredder have a vertical or square cutting 20 edge against which the beets are forced as the hopper bottom revolves, but this type of knife is often ruined by hard foreign matter, such as stones or pieces of iron, which in coming into contact with the cutting edge, which is necessarily very thin 25 and sharp, breaks this edge and hence makes the knife useless. As these knives are rather expensive, such breakage is an item of considerable importance. It is one of the objects of this invention to so form the cutting 30 edge of the knife that it is almost impossible for it to be broken in the manner above described.

Another object of the invention is to so 35 support the cutting edge of the knife by means of a throat-piece that foreign matter will not be wedged in the throat of the shredder.

Another object is to make the throat- 40 piece adjustable so as to regulate the depth of cut to be made.

A further object of the invention is to so 45 form the throat-piece that the beets will always present a surface for the knife to cut.

The invention consists in a knife for beet-shredders and the like, having a cutting edge inclined rearwardly from bottom to top and adapted to coöperate with a throat-piece 50 which is slotted to support and shield the cutting edge of the knife and provided with means for adjusting it with relation to the knife to vary the cut made, and having grooves in its upper face to insure the presentation of the articles to be cut in such 55 manner that they will always present a sur-

face for the knife edge to cut; all as I will proceed now to explain and finally claim.

In the accompanying drawings illustrating the invention, in the several figures of 60 which like parts are similarly designated, Figure 1 is a plan view of a block on which the shredding knife and its coacting parts are mounted. Fig. 2 is a vertical section taken in the plane of line A—B, Fig. 1. 65 Fig. 3 is a fragmentary perspective view of the knife. Figs. 4 and 5 are side elevations of two modified forms of knife.

The cutter-block 1 has a central discharge opening 2, at one side of which the knife 3 is suitably secured by means of screws 4 or other fastenings in a recess 5. In a recess 6 at the opposite side of the opening 2 is mounted a throat-piece 7, held rigidly in position by means of screws 8 which clamp 70 it down upon the upper ends of adjusting screws 9. Although I have herein illustrated this particular means for adjusting the throat-piece with relation to the knife, it is obvious that other suitable means might be 75 80 equally well used.

The knife 3 has an attaching plate 10, from which extends the cutter proper, formed in a series of flutes 11 tapered to a sharp edge, and having downwardly projecting blades 12, also sharpened on their edges 13.

In the knives now in use the cutting edge is vertical, but I find that in the use of knives so made hard foreign matter, such as 90 stones and pieces of iron, will strike abruptly against the edge with such force as to break it and thereby ruin the knife. In the knife of this invention the cutting edge 13 is beveled, or inclined rearwardly from bottom to 95 top, so that when any foreign substances strike it they will tend to ride over rather than jam against it.

The throat-piece 7 is provided in one edge with a series of slots 14 so spaced as to receive the blades 12 and prevent lateral movement thereof sufficient to break them. Furthermore, the tongues 15 formed by these slots extend between the blades 12 sufficiently far and in such manner as to prevent the 100 105 openings from becoming clogged.

When beets are shredded with a machine having knives of this type, the knife makes a cut fluted in contour like itself, and it sometimes happens that when the same beet 110 is again presented to the knife the flutes will register with the flutes of the knife and the

beet will merely slide over the knife without being cut. To obviate this the upper face of the throat-piece 7 is provided with grooves 16 in line with the blades 12, and any beets presented to the knife as above described, will be sufficiently lowered with respect to the knife to admit of a cut being made.

Although the preferred form of knife has a straight cutting edge 13, as shown in Figs. 1, 2 and 3, the edge may be made either convex or concave, as shown in Figs. 4 and 5 respectively.

Although the operation of the device seems obvious, it may be well to say that as the hopper bottom revolves, the beets are pressed down on the bottom by their own weight, and the knives are drawn under them to shred them, the shreds passing between the blades 12 and out of the opening 2 to a receiver.

It is to be understood that I do not limit my invention to the particular details of construction herein shown and described, as it is obvious that various changes may be made without departing from the spirit of the invention or the scope of the appended claims. Nor do I wish to limit its application to beet shredders alone, as it may be equally well used otherwise.

What I claim is:—

1. A cutter for beet shredders and the like comprising a cutter block having a discharge slot, a fluted knife secured to the block on one side of the slot and having its cutting edge extending over the slot and blades depending from the lower parts of the flutes and projecting forwardly therefrom, said blades having cutting edges inclined downwardly and forwardly from the cutting edge of said knife, and a throat piece projecting from the opposite side of the slot and having grooves in its projecting end into which the forward ends of said blades extend, and intervening tongues.

2. A cutter for beet shredders and the like comprising a cutter block having a discharge slot, a fluted knife secured to the block on one side of the slot and having its cutting edge extending over the slot and blades depending from the lower parts of the flutes and projecting forwardly therefrom, said blades having cutting edges inclined downwardly and forwardly from the cutting edge of said knife, and means for supporting the forward ends of said blades against lateral movement.

3. A cutter for beet shredders and the like comprising a cutter block having a discharge slot, a fluted knife secured to the block on one side of the slot and having its cutting edge extending over the slot and blades depending from the lower parts of the flutes and projecting forwardly therefrom, said blades having cutting edges inclined downwardly and forwardly from the cutting edge of said knife, and a throat piece projecting from the opposite side of the slot and having grooves in its projecting end into which the forward ends of said blades extend, the upper surface of said throat piece having alternate grooves and ridges in line with the blades and flutes, respectively.

4. A cutter for beet shredders and the like comprising a cutter block having a discharge slot, a fluted knife secured to the block on one side of the slot and having its cutting edge extending over the slot and blades depending from the lower parts of the flutes and projecting forwardly therefrom, said blades having cutting edges inclined downwardly and forwardly from the cutting edge of said knife, and a throat piece projecting from the opposite side of the slot and having grooves in its projecting end into which the forward ends of said blades extend, and intervening tongues extending substantially to the fluted cutting edge of said knife.

5. A cutter for beet shredders and the like comprising a cutter block having a discharge slot, a fluted knife secured to the block on one side of the slot and having its cutting edge extending over the slot and blades depending from the lower parts of the flutes and projecting forwardly therefrom, the cutting edges of said flutes and blades being forwardly and downwardly inclined, and a throat piece projecting from the opposite side of the slot and having grooves in its projecting end into which the forward ends of said blades extend, and intervening tongues.

6. In a cutter for beet shredders and the like, a knife having a fluted cutting edge and having blades on its under side extending in planes parallel with the flutes and projecting beyond said fluted cutting edge, the cutting edges of said blades being inclined downwardly from said fluted cutting edge.

In testimony whereof I affix my signature.

FRANK G. TERRY.
